UNITED STATES PATENT OFFICE

ALFRED C. LONG, OF CADIZ, OHIO

DESIGN FOR A WOODEN GUTTER

Application filed November 18, 1929. Serial No. 33,481. Term of patent 14 years.

To all whom it may concern:

Be it known that I, ALFRED C. LONG, a citizen of the United States of America, residing at Cadiz, in the county of Harrison and State of Ohio, have invented a new, original, and ornamental Design for a Wooden Gutter, of which the following is a specification, reference being had to the accompanying drawing, forming a part hereof.

In the drawing:

Figure 1 is a front elevation of a wooden gutter showing my design, and

Fig. 2 is a cross section on the line 2--2 of Fig. 1.

A gutter formed in accordance with this design has its outer or front face provided with an intermediate portion having the form of an ogee curve in cross section and located between upper and lower relatively narrow flat surfaces. Above the upper one

of these narrow surfaces the gutter is formed with a flat surface which is a great deal deeper than the narrow face and is offset forwardly therefrom and between the lower flat surface and lower edge of the gutter is formed a concaved surface. Therefore, the gutter when viewed in front elevation has a deep flat strip or surface along its upper portion and a concaved surface of similar depth along its lower portion, the intermediate portion of the front face being of an ogee formation and distinctly set off from the upper and lower portions by flat strips or surfaces of less depth than the upper surface.

I claim:

The ornamental design for a wooden gutter, as shown and described.

ALFRED C. LONG. [L.S.]
